Application December 12, 1941, Serial No. 422,630

10 Claims. (Cl. 206—41.2)

This invention relates to the packaging of merchandise items and while specifically disclosed for the packaging of cigarettes it is understood that the invention is of general application to other items.

One object of the invention is to provide a multiple package for merchandise items in which the items have individual coverings and are joined together in package form with the items individually removable for use without disturbing the remaining items in the package.

Another object of the invention is to provide an improved individual covering for merchandise items.

Another object of the invention is to provide an improved individual covering for merchandise items having provisions for joining into multiple packages and facilities for individual removal and opening of the items.

Another object of the invention is to provide a multiple package for merchandise items in which consumption of individual items is effected without opening of the coverings of unused items which remain until consumed.

Other objects and features of the invention will be readily apparent to those skilled in the art from the following specification and appended drawings, in which:

Figure 1 is a view of a continuous wrapping strip to be used in carrying out the invention.

Figures 2, 3, 4 and 5 are views of successive steps in the wrapping of an individual item.

Figure 6 is a view showing the building up of a multiple package.

Figure 7 is a view of a completed package.

Figures 8, 9; 10, 11; 12, 13; 14, 15; and 16 show successively the removal of an item for consumption.

In the drawings, in which like reference numerals indicate like parts, the application of the invention to the packaging of cigarettes has been specifically illustrated. While the invention is particularly adapted to the packaging of cigarettes it is to be understood that other merchandise items may be similarly packaged according to the invention.

In Figure 1 there is shown a continuous wrapping of a form which may be effectively used to produce the package of this invention. The outer lines 1 indicate the original outline of the wrapping which may be of waxed paper, "Cellophane" or other material. This strip is cut as indicated by the full lines and tie points of uncut material are left as at 2 to maintain the individual wrappings in a continuous strip. The dotted lines 3

indicate the positions to be taken by the ends of the cigarettes and form an area within which printing or marking of the wrapping may be effectively placed. At opposite ends of the wrappings are left the securing tabs 4, as shown, cut at 5 to the lines 3. Large tabs 6 are provided for the joining of individual items.

The steps in the wrapping of an individual cigarette or other item are shown in Figures 2 through 5. In Figure 2 the wrapping has been rolled around the cigarette in the form of an encasing tube with the tab 6 extending therefrom. In Figure 3 the ends of the wrapping beyond the lines 3 are formed, first opposite the tabs 4 as at 7. The next step in Figure 4 is to fold inwardly the sides of the end material and in Figure 5 the tabs 4 are folded over the ends of the tube and secured in position by an adhesive at the points 8.

In Figure 6 the individual casings have been joined together in the forming of a multiple package. This is effected by the attachment of each tab 6 to the main body of the adjacent tube by an adhesive as at the points 9 and the joining by adhesive of the tubes themselves at 11.

In Figure 7 has been illustrated a complete package of twenty cigarettes in two layers of ten each joined as in Figure 6 and provided with an outer package wrapping as at 12 which may take any desired form. When the package is to be opened, the outer cover 12 may be removed and the package split into two convenient, flat and easily carried multiple packages of ten each.

The manner in which individual cigarettes are removed from a multiple package is illustrated in Figures 8 through 16.

In Figures 8 and 9 the right hand cigarette is starting to be unrolled. This initiates a tear of the encasing tube at the points 13 where the tab 6 joins the main body portion of the wrapping. In Figures 10, 11 and 12, 13 the tube is being progressively unrolled, the tearing at the tab edges continuing and leaving end caps on the cigarette which is finally detached from the package as shown in Figures 14, 15. Removal of end caps 14 is indicated in Figure 16 and the cigarette is ready for consumption. The portion 15 of the wrapping attached to tab 6 may be torn from the package and disposed of. It is seen that removal and consumption of the cigarette has not opened the seal to the other cigarettes in the package which remain undisturbed.

Many obvious advantages of packaging according to the present invention will be readily apparent, a few of which will be mentioned. The

individual items remain fresh and uncontaminated while the items are being consumed, they remain sanitary, readily show the number of items remaining, do not lose or absorb moisture, absorb odors nor spill crumbs. In a sense they form their own humidor while retaining easy dispensability for the consumer.

While certain preferred embodiments of the invention have been specifically disclosed it is understood that the invention is not limited thereto but is to be given its broadest possible interpretation within the scope of the following claims.

What is claimed is:

1. A multiple package for merchandise items comprising a plurality of items provided with individual coverings, means joining said items together in side by side relation into a flat group which is substantially self sustaining, means for removing an end item from the group without disturbing the others therein, and means whereby the removal of an item with a rotating motion effects unrolling of at least the main body portion of its covering therefrom.

2. A multiple package for merchandise items comprising individual coverings for the items, said coverings being in the form of tubes sealed at their opposite ends and having integral side tabs along at least a portion of their bodies, means joining said coverings together into a substantially self sustaining group including means joining the side tab on each tube to the body portion of the next adjacent tube.

3. A multiple package for merchandise items comprising individual coverings for the items, said coverings being in the form of tubes sealed at their opposite ends and having integral side tabs along at least a portion of their bodies, means joining said coverings together into a substantially self sustaining group including means joining the side tab on each tube to the body portion of the next adjacent tube and means joining said tubes directly to each other.

4. A multiple package for merchandise items comprising individual coverings for the items, said coverings being in the form of tubes sealed at their opposite ends and having integral side tabs along at least a portion of their bodies, means joining said coverings together into a substantially self-sustaining group including means joining the side tab on each tube to the body portion of the next adjacent tube and means joining said tubes directly to each other, and means whereby removal of an item from the group with a rotating motion unrolls at least a portion of the individual covering from the item.

5. A multiple package for merchandise items comprising individual coverings for the items, said coverings being in the form of tubes sealed at their opposite ends and having integral side tabs along at least a portion of their bodies, means joining said coverings together into a substantially self-sustaining group including means joining the side tab on each tube to the body portion of the next adjacent tube and means joining said tubes directly to each other, and means including said side tabs and coverings whereby removal of an item from the group with a rotating motion unrolls at least a portion of the individual covering from the item, the covering

material tearing at lines determined by the junction of the side tab to the tube and leaving the removed item ready for consumption except for readily removable end caps of the covering material.

6. A multiple package for merchandise items comprising a plurality of individual packages for individual items, each individual package comprising a main body portion encasing said item and including portions integral with said main body portion formed to provide end surfaces for the casing and integral tabs at the ends of the casing folded over said end surfaces to complete the same, said end tabs being adhesively joined to the main body portion and a side tab integral with said main body portion and extending therefrom, the individual packages being disposed in side by side relation with the side tab on each adhesively connected to the main body portion of an adjacent individual package to form a connected, multiple package.

7. A multiple package for merchandise items comprising a plurality of individual casings enclosing said items, said casings being disposed in side by side relation and an integral portion extending sidewise from each casing and adhesively joined to the adjacent casing, said integral portion adhering to the package when its item is removed and means whereby the act of removing the item tears at least a part of the casing from about the item.

8. A multiple package for merchandise items comprising individual rolled casings for the individual items having closed end portions sealing the items, said casings being disposed in side by side relation to form a flat package, unrolled portions on each casing adhesively joined to the adjacent casing to form a substantially self-sustaining package, and means whereby each item may be removed with an unrolling motion without disturbing the other items and which removes at least the main body of its casing which remains adhering to the package.

9. A multiple package for merchandise items comprising individual rolled casings for the individual items having closed end portions sealing the items, said casings being disposed in side by side relation to form a flat package, unrolled portions on each casing adhesively joined to the adjacent casing to form a substantially self-sustaining package, and means whereby each item may be removed either as a unit in its casing by breaking the adhesion of its unrolled portion to the adjacent casing or by an unrolling motion which removes at least a portion of the main casing from about the item.

10. A multiple package for merchandise items comprising individual rolled casings for the individual items having closed end portions sealing the items, said casings being disposed in side by side relation, an integral side tab on each casing adhesively joined to the adjacent casing, and means whereby removal of each item with an unrolling motion without breaking the tab from the package causes a continuous strip to be torn from the casing and leaves about the item separated closed tubes readily slid endwise from the item.
